UNITED STATES PATENT OFFICE.

ROBERT NEWELL, OF NEW YORK, N. Y.

PERMUTATION SAFETY-LOCK.

Specification of Letters Patent No. 8,145, dated June 10, 1851.

To all whom it may concern:

Be it known that I, ROBERT NEWELL, of the city of New York, lock manufacturer, have invented, made and applied to use 5 certain new and useful improvements in the construction of locks that are used for the vaults of banks or any place where more than usual security is required; that said improvements are partly based upon an invention 10 patented by me on the seventeenth day of September, one thousand eight hundred and forty-four, but these improvements differ with this former invention, first, in the fact that the tumblers and slides have a 15 direct connection when the lock is unlocked, so that on commencing to lock the tumblers lift and adjust the slides, independently of, but at the same instant, that the followers are lifted by springs, and at the half turn 20 of the proper key the slides are detached from the tumblers, but the slides are not detached from the followers, until the locking motion is completed, when any improper movement of the tumblers will not then affect 25 the slides themselves to permit the withdrawal of the bolt or the discovery of the positions in which the slides have been placed, while locking, whereas in the former invention, the slides were lifted by the followers and springs alone as these rose to follow the tumblers; secondly, these improvements comprise a means of preventing the introduction or use of any false instrument 30 or pick after any movement of the parts by making the first movement of the parts 35 cover the key hole; thirdly, these improvements comprise means of protecting a lock from the effects of gunpowder introduced at the keyhole, said improvements separately 40 and collectively comprising parts and movements and effects not included or implied in my former patent, and that the construction, operation, and effects of the said improvements are fully and substantially set forth 45 and shown in the following description and in the drawing annexed to and making part of this specification of my said improvements, in which parts shown in my former patent are also shown and used, but are associated with other and different parts.

The Figure 1, is a full elevation, representing the entire lock, when unlocked, fitted with these improvements, the cover plate being removed; Fig. 2, represents the inner 55 face of the cover plate; Fig. 3, is an elevation of the lock, complete, showing the ex-

terior of the cover plate, with the detector lever, and key hole guard, and cam point to move the second detent of the bolt, as when the bolt is unlocked, and the parts at rest; 60 the position of the connections with the bolt, when locked, being shown by dotted lines; Fig. 4, represents the same as Fig. 3, when the parts are at the half motion, either way; Fig. 5, represents the interior, when half 65 locked, or unlocked, the detector tumbler *c*, and parting plates, seen in Fig. 1, all removed; Fig. 6, is an elevation of the bolt and dogs, as in the box, the tumblers, and other moving parts removed; Fig. 7, is a detached side elevation of the auxiliary followers to the tumblers, which lift the principal followers, and serve the purpose of parting plates to the followers; Fig. 8, is a 70 detached front and side elevation, of the followers; Fig. 9, is a detached front and side elevation of the slides; Fig. 10 is a detached elevation of the parting plates to the slides; Fig. 11, is a side elevation, and Fig. 12, is a plan from below, or inverted, of the 75 detent lever, and parts that take and hold the slides, when locked, and disengage from the slides, on unlocking, including the parts that govern this lever; Fig. 13, is a detached back and end elevation of the tumbler *c*, that 80 governs the detector lever, and key hole guard; and Fig. 14, is a vertical cross section of the powder cylinder, escape hole, safety block, and of the key, as in place, at 85 the line 1, 1, of Figs. 1 and 5.

Similar letters and numbers, as marks of reference, apply to the like parts, in all the several figures; and the figures are consecutively referred to, as needed, in aid of the following description, of the several parts.

A, is the box, or case, containing the working parts of the lock, 2, 2, 2, are studs, to support the cover plate, so as not to press on the working parts; 3, 3, 3, are screws and nuts, to retain the cover plate; B, is the bolt head; B¹, is the bolt shank; B², the bolt pendent, shown separately, in Fig. 6, as fitted with the locking talon 4, unlocking talon 5, detent notch 6, when unlocked, and detent talon 7, acting when locked; and with 100 a parallel slide slot 8, and stump 9. All these appear in the shank B¹, together with other parts hereafter referred to, as connected with other motions.

10 are the horizontal, and 11, the vertical 110 separating walls, in the box A, and 12, 13, are two parts of the vertical walls, shown as

fitted on the cover plate c , Fig. 2. These occupy the corresponding places, inside the box A. These walls, or partitions, are applied to the same use, as the like parts, that are described and claimed in my patent of seventeenth day of September, one thousand eight hundred and forty four, and are therefore distinctly disclaimed herein. a , are the tumbler plates, having legs a^1 , passing to the right of the key hole, between guide studs 14, and with arms a^2 , at the top sliding between guide studs 15, 15. These parts insure the vertical motion of the tumblers a , when lifted by the key bits, or other means, acting on the arc between the legs and walls; the arms a^3 to the left pass inside of the parts 11, and 12, of the vertical walls. Each tumbler is fitted with a horizontal opening, each to take the arm of a separate depressing lever a^4 , mounted on one stud 16, as a fulcrum, and fitted each with a spring 17, the operation of which is, to depress the points of the levers, and keep the tumblers down. Each tumbler is also fitted with an elbow a^5 , to the arms a^3 , each elbow finishes as a tenon 18, for a use shown hereafter. Above and behind the tumblers, a detent dog and tooth a^6 , on a stud 19, takes the detent notch 6, on the bolt shank B^1 , when unlocked; and takes the detent talon 7, when locked; and is fitted with a spring 20, operating to keep the detent down to the bolt shank, except when raised by the pin 21, which overlies the whole of the tumblers a , so that the dog is raised, and leaves the bolt so far free to move, when any one of the tumblers is fully lifted from below. The tumblers are kept separate, by parting plates a^7 , having lips 22, as is shown in my patent of the seventeenth September 1844.

a^8 , see Fig. 7, are both parting plates and movable auxiliary followers to the principal followers, and have lips 23, that support the lower ends of the principal followers, and carry them up, when lifted, as hereafter shown. The principal followers a^9 , shown detached in Fig. 8, are fitted with jaws 24, having indents, or saw teeth cut on their ends, end are placed with their lower ends on the lips 23, of the auxiliary followers a^8 , so that the upper sides of the lips 23, support the shank a^9 of the followers, and the under side of each lip 23, takes the point of a separate follower lever a^{10} , set on a fulcrum stud 26, with a spring 25, that constantly tends to raise the auxiliary followers a^8 , and followers a^9 , but is not strong enough to raise these, against the springs 17, until the tumblers are raised, to lock or unlock the bolt. The followers and their parting plates are kept in place by the studs 27. On the bolt pendent B^2 , is a guide plate b , and studs 28, serving as vertical guides to the slides b^1 , shown detached in Fig. 9, as made with

tongues 29, that fit into the jaws 24, of the followers a^9 , the points of the tongues being indented, in the same manner as the ends of the jaws 24. Near the top, on the right of the shank, each slide has a mortise, or notch 30, that takes the tenons 18, on the ends of the elbows a^5 of the tumblers; and on the rising of the tumblers a , the springs 26, and levers a^{10} lift the auxiliary followers a^8 , and followers a^9 , so that though the tumblers lift the slides, independently of the followers, the followers move at the same instant with the slides. On the opposite side of the shank b^1 , each slide is fitted with teeth 31, these parts are kept separate, by the parting plates a^8 , shown in the detached Fig. 10. Above the slides b^1 , a fulcrum 32, on the bolt shank B^1 , carries a detent lever b^2 , fitted as shown in Figs. 1, 5, 11, and 12, with a tusk 33, taking and holding the teeth 31, on the slides, at the height to which the tumblers may have raised them, as shown in Fig. 5. The lever b^2 , has an arm b^4 , projecting under the bolt head B, the end of this arm lies against the end of a parallel block 34, on the bracket b^3 , that is screwed on the box A, and the end of the arm b^4 , is made with a hook 36, that when unlocked, lies between the block 34, and stud 35, that is fitted on the bracket b^3 ;

On locking, the block 34, keeps the arm b^4 , from swinging forward, until the lever b^2 , is vertical; when the movement, on the center 32, has carried the end of the arm b^4 , below the block 34, and at the same time, placed the tusk 33, in the teeth 31, to hold the slides; and on unlocking, the tusk 33, holds up the slides, while the jaws 24, take the tongues 29, and until the tenons 18, take the notches 30, in the slides, at this instant, the stud 35, takes and holds on the hook 36, on the arm b^4 , and detaches the tusk 33, from the teeth 31, on the slides, and leaves them free to descend with the tumblers and followers. At b^5 , a crank lever, on a fulcrum 37, with a spring 38, carries a vertical dog b^6 , that takes in a notch, or talon, 39, on the pendent B^2 , the other end of the lever carries a tusk 40, that takes notches, near the lower ends of the auxiliary followers, a^8 , and followers a^9 . When any one of the tumblers is improperly lifted, so as to lift the detent dog a^6 , and pressure applied to the talon 5, causes, or allows, an end shake to the bolt, in the least degree, the top of the dog b^6 , enters the notch or talon 39, in the bolt pendent B^2 , and the spring beneath makes the tusk 40, enter the notches in front of it, this both holds the followers, and auxiliary followers, that are in their correct position, and prevents any other follower from lifting, with any other tumbler, until the power on the talon 5, is taken off, and the proper key applied to the lock; and if the least motion is given to any other tumbler, the tusk causes

a scraping sound, that deadens the sound of any other motion, and prevents detection of the position of any other part, by the sound produced on the part itself; b^s , is a 50 detent dog, on a fulcrum 41, with a spring 42, taking the notch 43, in the lower back end of the bolt shank B^1 , when unlocked, and taking the talon 44, when locked; a pin 45, projects through a horizontal slot in the 55 cover plate, to take and be acted on, by the campointed arm c^6 , of the detector lever D. A small wall 46, is placed under the tumbler legs, and between the powder cylinder c^4 , and the dog b^s , to stop any pick from reaching the dog, and prevent any powder reaching that part of the lock.

c , is the tumbler that governs the movement of the detector lever D, and key hole guard c^3 , having on the back, a pin 47, that 60 overlies the whole of the tumblers a , and a second pin 48, on the same side, that overlies the jaws 24, of the followers. In front, and at top, a pin 49, comes through a vertical slot, in the cover plate C, into a radial slot, in 65 the shortest arm c^1 , of the lever D, this works on a fulcrum 50, with a spring 51, set to lift the longest arm c^2 ; these carry a segment 52, that works over a horizontal slot in the cover plate C, which is fitted to pass a stump 53, on the bolt B, which stump lies before the 70 segment 52, on a lip, when the bolt is locked, as shown by dotted lines Fig. 3; and a circular slot 54, behind the segment 52, takes the stump 53, as the bolt is retracted, as 75 shown by the full lines, in Fig. 3. The detector lever D, carries also a covering plate c^3 , with a notch 55. As the lever D, swings in opening or shutting the lock, this notch passes a neck 50, in the key shank, which 80 neck is made around the shank, next above the drill pin cylinder 66, of nearly the same size as the drill pin 57; and these parts are so adjusted, that the plate, c^3 , comes over the key hole, when the tumbler c , is raised, so 85 that if the cylinder c^4 , is moved, for the purpose of blowing powder into the lock, by a blow pipe, the plate c^3 , prevents the introduction of a blow pipe after moving the cylinder c^4 ; and if the blow pipe is introduced 90 first, the cylinder c^4 , will not move, because the plate c^3 , will stop against the blow pipe, and prevent any further movement of the part, between itself, and the cylinder c^4 .

In the plate A, see Fig. 6, a circular 95 groove 58, receives the inner end of the powder cylinder c^4 , and a similar groove 59, on the inside of the cover plate c , receives the outer end of the powder cylinder, around the key hole; c^5 , are cam flanches, around the cylinder c^4 , the points 100 60, of which take the arc of, and raise the tumbler c , so soon as the key, or pick, commences to turn the cylinder c^4 ; and by raising the tumbler c , lifts the arm c^1 , of the 105 detector lever, depressing the longer arm,

so that the plate c^3 , comes over the key hole; the notch 55, passing the neck 56, in the key shank. A slot 61, in the cylinder c^4 , permits the key bits to pass in, and a stop block 62, underlies the slot 61, when at rest, 110 so that very little more gunpowder can be placed into the lock, through the key hole, than the cylinder c^4 , will contain, and a groove in the block 62, leads to a hole 63, through the case A, by which powder will 115 run out, unless the hole is plugged; and immediately under the drill pin 57, and above the block 62, an opening is made through the case A, that receives a block 64, fitted in so tight, as not to shake out, but to be 120 easily driven out behind by an explosion of gunpowder, placed in the cylinder c^4 , and thereby vent the force of the explosion, without injury to the lock, even if the hole 125 63, below, is plugged.

A guard plate 65, on the lever D, to the right of the key hole, prevents any powder going that way, between the lock and the door; and also intercepts any pick put in, to act on the pin 45, and move the dog b^s . 130 The cam formed piece c^6 , is riveted on under the plate c^3 , and passes below the plate 65, as shown by separating lines, so that if a drill, or other means are applied to remove the plate c^3 , the plate c^6 , drops away, and 135 still leaves the pin 45, and dog b^s , clear of any pick; but in this case, the lock cannot be opened, even with the proper key, until the door plate is bored through, to reach the pin 45. When the lock is properly opened, or 140 closed the cam point c^6 , forces the pin 45, to the right, and in either case, releases the dog b^s , from the shank B^1 , and allows the motion of the bolt, the retraction of the 145 parts allows the spring 42, to replace the dog b^s .

The key shank and bow d, are shown in place in Fig. 14, with the neck 56, to take the notch 55, and cylinder 66, to take the drill pin 57, with the standing bits 67, and shifting bits and screws 68, all as usual, 150 in keys of this class.

On three of the sides of the lock box A, a notch 69, is cut in, that serves to pass out, and waste, a considerable quantity of gun powder; and if gunpowder is, by any means, exploded between the lock plate and the door, the violence of the explosion spends itself through these openings.

It will be understood, by the foregoing 155 description of the construction, that the operation of these parts is as follows: On the key being introduced, at the key hole, and turned to lock the bolt, the standing bit take one edge of the slot 61, and carry the cylinder c^4 , around with them, the upper point 60, of the interrupted flanches c^5 , taking the arc of the tumbler c , lifts that vertically, the remainder of the flanch holding the tumbler; the pin 49, at the same time lift- 160

ing the short arm c^1 , of the detector lever D, moves the longer arm c^2 , downward, carrying the plate c^3 , laterally over and closing the key hole, the notch at 55, inclosing the neck 56, or the key shank; the cam point c^6 , taking the pin 45, removes the dog b^8 , from the notch 43; the motion taking down the stop 52, clear of the stud 53. The further rotation of the key, lifting the tumbler a , 10 raises the detent dog a^6 , above the bolt, by the pin 21, so that when the standing key bit comes in contact with the locking talon 4, the lip 52, behind the stud 53, as shown by dotted lines in Fig. 3, at the same time 15 removing the key hole cover c^3 , and notch 55, so that the key can be withdrawn. It will be understood, that on completing the locking, the dog b^6 , is depressed by the projection beyond the talon or notch 39, so that 20 the tusk 40, does not touch the followers a^9 , or auxiliary followers, and these, on unlocking, are raised to the proper height, before the bolt commences to move.

On the unlocking, the same motions of the 25 principal tumblers, and followers, and detector tumbler and lever take place, up to the time the key bit takes the unlocking talon 5, when both the detent dogs a^6 , and b^8 , are detached, and the bolt is at liberty to move, 30 carrying the slides b^1 , and lips 30, to take the tenons 18 of the tumbler arms, and the tongues 29 into the jaws 24, of the followers, and at the moment the tenon 18, takes the notch or mortise 30, the stud 35, on the 35 bracket b^3 , has taken the hook 36, on the under side of, the arm b^4 , and holding the lever b^2 , against the motion of the bolt, detaches the tusk 33, from the teeth 31, and leaves the slides at liberty to move down- 40 ward, with the followers and tumblers, as the levers a^4 , and springs 17, act on the collective parts to depress them, the lifting spring 51, raising the longer arm of the lever D, and depressing the shorter arm c^1 , assists 45 to send down the pin 49, on the tumbler c , and with it the pin 48, and any one, or more, of the followers and slides that may stick from dust, or other local cause; this part of the lock being needed, where a lock is, from 50 necessity, used in a horizontal position, or when, from any cause, the tumblers have been separately moved, by other means than the right key. In the foregoing movements, by the right key, the covering plate c^3 , has 55 acted with the other parts, the notch 55, having taken the neck 56, in the key shank, and covered the key hole, at the commencement of each movement, and uncovered it at the close.

60 These being the movements with the true key, the effects of entering a false key, or pick, will be more readily understood to be as follows: If one false instrument is put into the key hole, so as in any degree to ro- 65 tate the cylinder c^4 , the points 60, instantly

lift the tumbler c , and through the lever D, send the key hole cover plate c^3 over the key hole, this shuts out a second instrument; if two, or more instruments, are put in together, and rotated, and held, so that one point passing the slot 61, reaches the talon 5, and the second is employed to lift any given tumbler, the given follower will raise and the detent dogs a , b , and b^8 , will, at this moment, both be detached from the bolt shank, and the pressure on the talon 5, will give an end motion to the bolt, and bring the teeth, on the ends of the tongues, 29, and jaws, 24, into contact, at the same time placing the small talon 39 and B^2 , over the top of the small dog b , b , which leaves the spring 38, at liberty to press the tusk 40, into the notches on the lower ends of the auxiliary followers a^8 , and followers a^9 , so that if even a third, or more instruments, can be got in, to act on the tumblers, the remainder followers cannot move, until the bolt is released, and replaced; and during these false movements, no indication can be obtained, of the positions in which the tumblers and 85 followers have left the slides, and by consequence, the bolt cannot be thrown back, to open the door.

If by any improper means, the locking talon 4, on the bolt shank should be reached, 90 so as to take off the least portion of the lower angle, the key will not throw the bolt entirely out, on locking, and the upper and forward angle of the part 52, on the detector lever D, will stop under the back edge of the stump 53, and hold the part c^3 , over the key hole, thereby preventing the key coming out. By this, the owner of the lock will at once know that an improper attempt has been made to prevent the full locking action 95 of the bolt, and thereby enable some one else to open the lock, by the counteracting parts not being fully in their places, as they must be, when the key hole is uncovered, whether the bolt head B, be fully out, as when properly locked, or in place when unlocked.

The effects of exploding gun powder in 100 the lock have been detailed, in describing the parts, and need not be repeated here. The manner of applying the separating walls, or guard plates 10, 11, 12, and 13, being covered in my patent of 17 Sep., 1844, is expressly disclaimed herein; and the mode claimed, in the same patent, of combining and arranging the followers, jaws, tumbler 105 arms, auxiliary followers, slides, and tongues, so far as is therein set forth, is also disclaimed herein the improvements on these parts being separately claimed, as acting with the old parts, as herein set forth.

What I claim as new, and of my own invention and improvement, and desire to secure by Letters Patent of the United States, is,

1. The application of the lever b^5 , and dog 115

b⁶, with the tusk 40, to be acted on by the talon 39, and allow the spring 38, to throw the tusk 40, into the notches on the lower part of the followers and auxiliary followers, so as to prevent any motion of these parts, if any of the tumblers are lifted, after any end shake motion has been given to the bolt, by any improper attempt to unlock it.

10 2. The combination of the tumblers *a*, slides *b¹*, and followers *a⁹*, through the tensons 18, notches 30, tongues 29, and jaws 24, to lift the slides *b¹*, and followers *a⁹*, to the same extent as the tumblers *a*, are lifted by 15 the key sections, on locking the bolt; and to sustain the slides *b¹*, until the tusk 33, takes the notches 31, on the slides, and holds them, so that the bolt cannot be retracted, until all the tumblers *a*, are lifted to meet the 20 notches 30, and allows the springs 25, levers *a⁶*, and auxiliary followers *a⁸*, to lift and place the followers *a⁸*, in the same positions as when the bolt was projected; substantially as described and shown.

25 3. The mode described and shown, of so arranging and combining the cylinder *c⁴*, by the flanches *c⁵*, angles 60, tumblers *c*, and *a*, and pins 47, and 49, with the detector lever D, at the part *c¹*, so that no one of the tumblers *a*, can be separately lifted, without placing the part *c³*, of the detector lever over the key hole, with the edges of the notch 55, covering the open space around the drill pin 57, by which arrangement no movement of 30 the cylinder *c⁴*, can be made, without producing the same effect; so that if powder is introduced into the cylinder *c⁴*, and the cylinder is moved, with the intent of entering 35 a blow pipe to spread the powder on either 40 side of the cylinder, the part *c³* and notch

55, instantly cover the key hole, and prevents the entry of the blow pipe for such a purpose; these parts being constructed, arranged, and operating substantially as described and shown.

4. The combination of the cylinder *c⁴*, block 62, and hole 53, to receive and pass out any gunpowder put in, for the purpose of exploding to destroy the lock; and at the same time, prevent the powder from reaching any other part of the interior of the lock.

5. The application of the safety valve block 64, to vent the explosion of any gunpowder, that may be confined in the cylinder *c⁴*, by plugging both the key hole, and the 55 hole 63.

6. The mode of fitting the key hole cover *c³*, with the notch 55, on the detector lever D, to match the neck 56, on the key shank, such means also preventing the introduction of 60 any pick, or false instrument, after any movement has been given to the cylinder *c⁴*, by the notch 55, being as small as the drill pin 57.

7. The application of the guard piece 65, 65 on the detector lever D, to prevent a pick reaching the pin 45, of the detent dog *b⁸*.

8. The application of the cam pointed piece *c*, *b*, on the detector lever D, to move the pin 47, and detent dog *b⁸*, so attached, 70 that if the key hole cover is cut or drilled off, the piece *c*, *b*, falls away, and leaves the detent dog *b⁸*, still holding the bolt.

In witness whereof, I have hereunto set my signature, this twenty ninth day of July, 75 one thousand eight hundred and fifty.

ROBT. NEWELL.
